UNITED STATES PATENT OFFICE.

CHARLES A. CARSCADIN, OF CHICAGO, ILLINOIS, ASSIGNOR TO AMERICAN STEEL FOUNDRIES, OF CHICAGO, ILLINOIS, A CORPORATION OF NEW JERSEY.

YOKE FOR DRAFT GEARS.

Application filed October 17, 1921. Serial No. 508,804.

To all whom it may concern:

Be it known that I, CHARLES A. CARSCADIN, a citizen of the United States, residing at Chicago, in the county of Cook and State 5 of Illinois, have invented certain new and useful Improvements in Yokes for Draft Gears, of which the following is a specification.

This invention relates to railway draft 10 gears and its object is to provide a yoke of simple and substantial construction and means for readily and easily securing the draw bar butt therein and for insuring retention of the draw bar butt under usual operating conditions.

A further object of the invention is to provide means whereby a transverse key may be employed for securing the draw bar butt in the yoke under conditions which will insure 20 a maximum strength and efficiency and prevent accidental dislodgment of the key and consequent release of the butt.

With these and other objects in view, which will be pointed out hereafter, I have 25 illustrated the invention in a selected embodiment in the accompanying drawings in which—

Fig. 1 is a side elevation showing the draw 30 bar butt, yoke and key in assembled relation;

Fig. 2 is a transverse section on the line 2—2 of Fig. 1;

Fig. 3 is a perspective view showing the 35 parts in position to be assembled.

Referring to the drawings, the yoke 10 comprises an upper member 11 and a lower member 12 connected at their rear ends by the end portion 13 and provided at the front with sides 14 to form, in effect, an integral hooded forward portion. These sides are 40 provided with longitudinally extending channel guides 16 located parallel with and approximately midway between the upper member and the lower member and extending 45 preferably from the rear ends of the sides forward a sufficient distance so that the key 18 will be protected against dislodgment by its ends abutting against the sides of the yoke when the parts are assembled as shown 50 in Fig. 1. The shoulders 17 at the forward ends of the channel guides limit the movement of the key forwardly in the yoke and the draft rigging which is arranged within 55 the yoke between the coupler butt and the end portion 13 will form a yielding limit to

the movement of the draw bar butt, and consequently of the key rearwardly in the yoke. The size of the sides may be reduced to save weight but the channel guides should be of a length sufficient to prevent the ends of the 60 key from being exposed completely under usual working conditions.

The parts can be very easily assembled by introducing the draw bar butt into the hooded end of the yoke and moving it back sufficiently to clear the key opening 20 therein, whereupon the key 18 is slipped into the key opening and the draw bar butt is moved forward to its normal position, the ends of the key sliding in the channel guides 16, and for this purpose the channel guides should be of a sufficient depth to form a safe and substantial seat for the ends of the key. Under normal working conditions the key will never be pushed rearward far enough to 70 completely expose its ends clear of the sides of the yoke consequently there will be no danger of the key becoming disconnected from the butt to release the butt from the 75 yoke.

In order to provide a yoke with channel guides in accordance with my invention, and without materially enlarging or increasing the weight of the yoke, I prefer to make the yoke with outward side projections 19 and 80 form channel guides therein whereby a substantially uniform section may be provided for the yoke and with the channel guides therein. I do not wish to limit myself to the particular construction and proportion of 85 parts shown and described as it may be found desirable to vary therefrom to meet different conditions and to adapt the invention for use with other railway equipment, and therefore I reserve the right to make all 90 such changes in the form, proportion and arrangement of parts as fairly fall within the spirit and scope of the invention.

The invention provides a strong and substantial yoke with means for readily and easily securing the draw bar butt in operative position therein, and the invention involves the use of but a single movable part for securing the draw bar butt in the yoke and in such a manner that the securing 100 means is protected and held against accidental separation from the draw bar or displacement from its retaining assemblage with the yoke. It will be readily understood that the draw bar butt may be easily 105 110

taken down by simply pushing it back far enough in the yoke to permit removal of the key and then withdrawing the butt from the hooded end of the yoke. The invention 5 entirely dispenses with the necessity of employing keys of special construction or cotter pins or other devices for holding the key in place and thereby simplifies the construction and reduces the number of parts 10 necessary to make a complete operative assemblage.

I claim:

1. The combination with a draw bar, of a yoke for draft gears having a hooded forward end and channel guides in its sides 15 within the yoke, said channel guides having shoulders at their forward ends and openings at the rear end of said guides, the hooded end being adapted to receive the draw bar butt when the draw bar butt is inserted into it by movement in a direction substantially parallel to a longitudinal plane through the guides, and a key adapted to engage the draw bar butt and to have its 20 ends operatively engaged with said channels guides, the draw bar butt and yoke being adapted to permit insertion of the key into place without angular displacement of the draw bar butt relative to the yoke.
2. The combination with a draw bar, of a yoke for draft gears having an upper member and a lower member connected together at their rear ends, and sides connecting said members together at their forward 25 ends, said sides having longitudinal grooves formed therein within the yoke and extending parallel to the top and bottom members substantially midway therebetween, said upper and lower members being adapted to receive the draw bar butt when the draw bar butt is placed between them by movement in a direction substantially parallel to a longitudinal plane through the grooves, and a key adapted to be engaged 30 with the draw bar butt and to have its ends operatively disposed in said grooves, the

draw bar butt and yoke being adapted to permit insertion of the key into place without angular displacement of the draw bar butt relative to the yoke.

3. The combination with a draw bar, of a yoke for draft gears having an upper member and a lower member, sides connecting said members at their forward ends, the opposed faces of said sides having channel guides formed therein, said channel guides terminating at their front ends in shoulders and opening at their rear ends at the rear ends of said sides, said upper and lower members being adapted to receive the draw bar butt when the draw bar butt is placed between them by movement in a direction substantially parallel to a longitudinal plane through the guides, and a key adapted to be engaged with the draw 65 bar butt and to have its ends operatively engaged with said channel guides, the draw bar butt and yoke being adapted to permit insertion of the key into place without angular displacement of the draw bar butt relative to the yoke.

4. The combination with a draw bar, of a yoke comprising an upper member and a lower member, sides connecting said members at their forward ends, the opposed faces of the sides having grooves therein extending longitudinally of the yoke and parallel with the top and bottom members and substantially midway therebetween, said upper and lower members being adapted to receive the draw bar butt when the draw bar butt is placed between them by movement in a direction substantially parallel to a longitudinal plane through the grooves, together with a key carried by the draw 80 bar butt and having its ends disposed in said grooves, the draw bar butt and yoke being adapted to permit insertion of the key into place without angular displacement of the draw bar butt relative to the yoke.

CHARLES A. CARSCADIN.
